DRIVING TOOL FOR TUBULAR GROUNDING RODS

Harold C. Daniels, Woodbury, Conn., assignor to Chase Brass & Copper Co. Incorporated, Waterbury, Conn., a corporation

Application March 11, 1938, Serial No. 195,323

7 Claims. (Cl. 61—73)

The present invention relates to an improvement in driving-tools for tubular grounding-rods constructed of relatively-soft metals such, for example, as copper, which have a high degree of electrical conductivity and are superior for making and maintaining grounding-contacts.

The general object of this invention is to provide a driving-tool of improved construction which will facilitate the driving of soft-metal grounding-rods and thus render more available the superior electrical-conducting and ground-contacting qualities of these metals.

One of the objects of the present invention is to provide suitable and effective means to protect the upper end of a tubular grounding-rod constructed of relatively-soft metal, from deformation and mutilation, when said grounding-rod is driven under the recurring impacts of a driving-tool which embodies the protective means.

Another object of the invention is to maintain the predetermined size and shape of the tubular grounding-rod at its upper end during recurring impacts thereon by a driving-tool for the purpose of facilitating the subsequent attachment thereto of a wire-grounding cap or plug for electrical installations of various kinds.

With the above and other objects in view, as will appear to those skilled in the art, from the present disclosure, this invention includes all features in the said disclosure which are novel over the prior art.

In the accompanying drawing:

Fig. 1 is a side elevation of the driving-tool constructed according to the invention;

Fig. 2 is a side elevation of a tubular grounding-rod after it has been completely driven by the driving-tool, and a wire-grounding plug or cap attached thereto at the top;

Fig. 3 is an enlarged side elevation of the driving-tool shown in position on a tubular grounding-rod at the conclusion of the driving operation, the lower portion of the driving-head and the upper portion of the grounding-rod, being shown in section;

Fig. 4 is a transverse section on the line 4—4 of Fig. 3 as seen from below;

Fig. 5 is an enlarged side elevation of the driving-tool with the lower portion of the driving-head broken away and shown in section; and

Fig. 6 is a transverse section on the line 6—6 of Fig. 5 as seen from below.

According to the embodiment shown on the drawing, the invention is illustrated in connection with a tubular grounding-rod 10 of the character shown, described and claimed in the co-

pending application of George A. Hornbecker, filed March 12, 1938, under Serial No. 194,454, which may be constructed of thin-walled hard-drawn copper tubing and provided at the bottom with a rigidly-attached leading-point 11 of conical form. The tubular member 10 may vary greatly with respect to length, diameter and wall-thickness, depending upon local conditions surrounding any particular installation. Such a tubular member may vary in length from about two feet to eight or more feet and may vary in external diameter from about one-half inch to about one and one-quarter inch. The wall-thickness of said tubular member is preferably within the range of .025 inch to .035 inch approximately, for the purpose of providing maximum surface area for contact with the ground and at the same time for minimizing the amount of copper, or other relatively-expensive metal, required for a given installation.

While the driving-tool forming the subject-matter of the present invention, may be utilized for driving a tubular grounding-rod with or without a contained filler-medium, in the form shown on the drawing, the tubular grounding-rod shown is provided with a filler-medium comprising superposed sections 12 of hard wood having a sufficient degree of resilience to effectively support the tubular wall of the grounding-rod, said filler-medium being preferably compressible axially and expandable in transverse cross-section into substantially-rigid engagement with the inner wall of the tube. According to Fig. 3, the driving-tool has been illustrated at the conclusion of a driving-operation, the filler-sections having been axially-compressed and transversely-expanded to form a consolidated core organized with and forming a permanent part of the grounding-rod assembly. As shown best in Fig. 5, a reciprocatory driving-head 13 with which the driving-tool is provided, has a central cylindrical cavity which defines the outer cylindrical wall of an annular recess or driving-socket 14 having an inner end-wall or annular shoulder 15 whereby the recurring impacts of driving-head 13 are delivered to the upper end of the tubular grounding-rod. For the purpose of mounting a plunger-rod in the driving-head, the latter is provided with an axial socket 16 which extends upwardly from annular shoulder 15. Said plunger-rod comprises a portion 17 of relatively-larger diameter secured within the socket 16 with a shrinking-fit, a portion 18 of relatively-smaller diameter which is reciprocable within the upper end of the tubular grounding-rod, and a short 55

tapered portion 19 intervening between the portions 17 and 18. The portion 17 of the plunger-rod defines the inner wall of driving-socket 14 and is sized to slidably fit the inner wall of the tubular grounding-rod which is slidably engaged on its outer wall by the outer cylindrical wall of driving-socket 14.

From the foregoing description, it will be understood that during the recurring impacts of the driving-head 13 on the upper end of the tubular grounding-rod, the cylindrical walls of driving-socket 14 reciprocably engage the inner and outer tubular walls of the grounding-rod in such a way as to protect and reenforce them against deformation or mutilation which, otherwise, they would be subjected to. When the driving-head 13 is reciprocated by hand, the upper end of the tubular grounding-rod 10 is frequently retracted from the driving-socket 14. During a subsequent downward movement of said driving-head, the upper end of grounding-rod 10 strikes the tapered surface 19 which operates as a guide on the inner bore of the grounding-rod to register the upper end of the grounding-rod with respect to the driving-socket 14 wherein it is firmly supported and reenforced for the impact thereon of shoulder 15. For this purpose, the plunger-rod portion 17 is extended somewhat below the outer end of driving-socket 14 to effect a proper registry of the tubular upper end of the grounding-rod 10 by the tapered surface 19 before the upper end of the grounding-rod enters the driving-socket 14. To further facilitate this action, the driving-head is provided with a chamfered corner 20 extending around the aperture of the driving-socket 14. By means of the chamfered corner 20, slight irregularities in contour may be corrected in the wall of the tubular grounding-rod as the upper end thereof is guided into the driving-socket. The reciprocatory driving-head 13 is preferably constructed of tool steel and in the event that it is desired to employ a driving-sledge thereon, said driving-head is tempered to withstand the blows of the sledge.

As shown in Fig. 2, the leading-point 11 is preferably provided with a shank 12a which is driven into the lower end of tubular grounding-rod 10, the upper end of said shank serving as an anvil to receive recurring impacts directly transmitted thereto by the plunger-rod portion 18 when the driving-tool which forms the subject-matter of the present invention is employed in place of that shown and described in my co-pending application Serial No. 150,988, filed June 29, 1937. In this case, the plunger-rod of the driving-tool disclosed in the present application, is preferably constructed to serve the functions of the driving-plunger as described in the above-identified co-pending application while at the same time constraining the reciprocatory movements of the plunger-rod in the manner pointed out in the present case.

In many places, where the ground is relatively soft and of even texture, the tubular grounding-rod with or without a reinforcing core therein, may be sunk into the ground by a hand-reciprocation of a driving-tool constructed in accordance with the present invention. In other cases, where the ground is somewhat harder or denser and a grounding-rod provided with a consolidated core is preferably employed, the grounding-rod may be completely driven by the hand-manipulation of driving-head 13 or by means of a sledge for delivering recurring impacts upon

the inner core of the grounding-rod through the plunger-rod without the annular shoulder 15 coming into engagement with the upper end of the grounding-rod. In other cases, where the ground is unusually resistant and renders it desirable to use a grounding-rod provided with a consolidated core, said grounding-rod may be driven at first by means of impacts on the core within the grounding-rod and subsequently by means of a hand-operated or sledge-driven action of the driving-head 13 to engage its shoulder 15 with the top of the grounding-rod. From the foregoing description, it will be understood that in unusually resistant ground, a driving-tool of improved construction according to the present application may be employed in connection with a tubular grounding-rod of the character disclosed in the above-identified application of George A. Hornbecker. By means of this combination of devices, the driving operation may be carried on in such a way as to include, at first, the driving impacts delivered to the conical leading-point at the bottom through the core 12, which is materially reenforced and aided by an increased frictional engagement between the condensed core and the inner wall of the tubular grounding-rod, followed by recurring impacts of the driving-head 13 at the top of the tubular grounding-rod. In this way, exceedingly effective results may be obtained in driving tubular grounding-rods constructed of relatively-soft metal reenforced and operated upon in the manner described above.

The invention may be carried out in other specific ways than those herein set forth, without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. A driving-tool for tubular grounding-rods, comprising: a plunger-rod to reciprocate within the tubular grounding-rod, and a driving-head mounted on the upper end of said plunger-rod, said driving-tool being provided with an annular recess within the driving-head and concentric to the plunger-rod to receive the upper end of said tubular grounding-rod.

2. A driving-tool for tubular grounding-rods, comprising: a driving-head provided with a cylindrical cavity having a circular wall to slidably fit the exterior wall of a tubular grounding-rod; and a plunger-rod mounted in said driving-head and concentrically arranged with respect to said cylindrical cavity, said plunger-rod having a portion disposed within said cylindrical cavity of suitable diameter to slidably fit the inner wall of the tubular grounding-rod.

3. In a driving tool for tubular grounding-rods, a plunger-rod comprising a portion to slidably fit the bore of a tubular grounding-rod and a portion to deliver a driving impact within said grounding-rod; and a driving-head mounted on the upper end of said plunger-rod; said driving-head being provided with a central bore provided with a transverse end-wall constructed and arranged to impinge upon the upper end of said tubular grounding-rod.

4. A driving-tool for tubular grounding-rods, said driving-tool comprising a driving-head and a plunger-rod, said driving-tool being provided within the driving-head with an annular recess

having circular walls to slidably fit the inner and outer walls of a tubular grounding-rod and a transverse wall at the inner end of said annular recess to impinge upon the upper end of the tubular wall of said grounding-rod; and the said plunger-rod projecting from said driving-head in concentric arrangement with said annular recess, said plunger-rod being provided with a tapered portion adjacent to the outer end of said annular recess to center said upper end of the tubular wall therein.

5 5. In a driving-tool for tubular grounding-rods, a plunger-rod comprising a portion of relatively-larger diameter to slidably fit the bore of a tubular grounding-rod and a portion of relatively-smaller diameter to impinge upon a part organized with and forming a permanent part of a tubular grounding-rod within the interior thereof; and a driving-head provided with a central bore having a circular wall to slidably fit the outer wall of said tubular grounding-rod and forming with the exterior of said relatively-larger portion of the plunger-rod, an annular socket to receive the end of said tubular grounding-rod, 10 said annular socket being provided with an inner end-wall to impinge upon the upper end of the tubular grounding-rod while the inner and outer walls thereof are supportably engaged by the circular walls of said annular recess.

15 6. In a driving-tool for tubular grounding-rods, a driving-head provided with a cylindrical cavity at one end having a circular wall to slidably fit the outer wall of a tubular grounding-rod; a plunger-rod projecting outwardly from the inner

10 end-wall of said cylindrical cavity and having a portion within said cavity to slidably fit the inner wall of said tubular grounding-rod, said plunger-rod being provided with a lower-end portion to reciprocate within the grounding-rod and an intermediate tapered guide portion interposed between the aforesaid portion to slidably fit the inner wall of said tubular grounding-rod and said lower-end portion.

15 7. In a driving-tool for tubular grounding-rods, the combination with a reciprocatory driving-head provided with a cylindrical cavity having a circular wall to slidably fit the exterior surface of a tubular grounding-rod and with an annular shoulder arranged to deliver recurring impacts to the end of said grounding-rod, of a plunger-rod comprising a portion of relatively-larger diameter to slidably fit the interior surface of the tubular grounding-rod and disposed within said cylindrical cavity in concentric relation thereto; 20 a portion of relatively-smaller diameter to reciprocate within the tubular grounding-rod; and an intervening tapered portion for slidably engaging the inner bore of the grounding-rod to guide the upper end thereof onto the said portion of relatively-larger diameter, said portion of larger diameter forming with the cylindrical wall of said cavity an annular driving-socket which reciprocably houses the inner and outer surfaces of the upper end of said tubular grounding-rod during recurring impacts of said shoulder on the upper end thereof.
